UNITED STATES PATENT OFFICE.

EZRA S. BUCKNAM, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

FARE-BOX.

No. 901,778.

Specification of Letters Patent.

Patented Oct. 20, 1908.

Application filed March 30, 1908. Serial No. 424,179.

To all whom it may concern:

Be it known that I, EZRA S. BUCKNAM, a citizen of the United States, residing in Philadelphia, Pennsylvania, have invented 5 certain improvements in Fare-Boxes, of which the following is a specification.

My invention relates to certain improvements in boxes for collecting fares, particularly upon street cars of the type in which 10 the passenger pays the fare as he enters the car, although it will be understood that my invention can be used for collecting money and tickets for admission to places of amusement or to other places where such a device 15 can be utilized.

One object of the invention is to provide a detachable receptacle for the money and tickets.

A further object is to provide means for 20 locking the receptacle to the box and also to provide means for closing the receptacle when the lock is operated so that the receptacle can be detached from the box.

A still further object of the invention is 25 to provide means for opening the passage in the receptacle, through which the money and tickets pass from the box to the receptacle, when it is desired to gain access to the interior of the box.

30 In the accompanying drawings:—Figure 1, is a perspective view of my improved fare box; Fig. 2, is a vertical sectional view of the fare box; Fig. 3, is an enlarged perspective view of the receptacle; Fig. 4, is a transverse sectional view on the line 4—4, 35 Fig. 2; Fig. 5, is a detached view of the lock shown in Fig. 4; Fig. 6, is a longitudinal sectional view of the receptacle on the line 6—6, Fig. 4; Figs. 7 and 8 are diagrams 40 showing the mechanism in different positions; Fig. 9, is a plan view of the receptacle partly in section; Figs. 10, 11 and 12, are detached perspective views of parts of the mechanism; Fig. 13, is a view of a modification 45 of one of the locks; Fig. 14, is a sectional view illustrating a modification of the upper portion of the box; Fig. 15, is a view illustrating a modification of the slide mechanism; Fig. 16, is an elevation of one of the locks showing the internal mechanism of the 50 same, and Fig. 17, is a sectional view on the line 17—17; Figs. 4 and 16, looking in the direction of the arrow x.

In pay-as-you-enter cars it is desirable to

have a fixed box for the collection of the 55 fares so that a person entering the interior of the car from the platform can place the fare in the box, relieving the conductor of the handling of the fare, and it is also desirable to provide a receptacle for the fares 60 which is not accessible to the conductor or to any one outside the room in the depot where the money and tickets received are counted, and it is essential that the parts be so arranged that the receptacle will be open 65 for the reception of fares when it is placed in position in the box.

Referring to the drawings, A is the body of the box, made quadrangular in cross section in the present instance and tapered at 70 the top and having mounted upon the top a ticket receiving section B, preferably made of a metallic frame glazed on all four sides, with deflecting plates b and a movable chopping platform b', so that when the fare is 75 placed in this receptacle the person paying the fare, as well as the conductor, can see the fare pass from one deflector to the other and rest upon the chopping platform, and after the conductor has examined the fare 80 he simply operates a lever b² connected to the platform b' and allows the fare to pass into the box.

In the base of the box is a drawer or receptacle D, and extending from the upper 85 portion of the box to the drawer or receptacle is a chute a through which the fare passes into the receptacle. In the chute a are hinged valves a'—a' which close the chute should the fare box be inverted, preventing 90 the escape of fares from the receptacle. The receptacle D has a top plate d in which is a slot d' in line with the chute a and this slot is closed by a slide E having an opening e and actuated by the locking mechanism of 95 the receptacle.

F is a lock secured to the drawer and the bolt f of this lock engages a keeper a² on the box when projected so as to prevent the withdrawal of the drawer unless the lock is 100 turned to retract the bolt. In the present instance the spindle F' of the lock is connected to or forms part of a shaft I, as shown in Fig. 17, having a segment i provided with teeth which mesh with a rack e' attached to 105 the underside of the slide E, so that on the first movement of the spindle F' after the key is inserted in the lock the slide is moved

so as to close the slot d' , then on further movement of the spindle the bolt f of the lock is retracted, after which the receptacle D can be withdrawn from the box A.

5 In Figs. 4 and 5, I have shown the spindle F' provided with a handle f' and in the present instance the spindle has a portion f^2 which is engaged by a slide f^3 actuated by the locking mechanism in the cylinder f^4 .
10 The bolt f of the lock, as well as the shaft I, is actuated by turning the spindle; by this means the turning of the key simply releases the spindle and the turning of the spindle is accomplished by turning the handle f' , thus preventing the straining of the key. In some instances, as shown in Fig. 13, the locking mechanism in the cylinder f^4 may be connected directly to the spindle and shaft, so that the key not only actuates the locking mechanism but turns the shaft and retracts the bolt.

15 The segment i is mounted loosely upon the shaft I and has a slot i' in its hub, into which projects a pin i^2 , so that there will be a certain amount of lost motion on turning the shaft. There is also a certain amount of lost motion between the spindle F' of the lock and the bolt f as shown in Fig. 16, so that on turning the spindle F' the shaft I 30 will be turned a given distance before the bolt f is moved, thus moving the slide E which will close the slot d' before the bolt f is retracted to allow the removal of the drawer or receptacle D.

20 35 The spindle f^2 of the lock has arms f^5 which contact with projections f^6 on the bolt when the said spindle is turned. The spindle is allowed to move a certain distance before it actuates the bolt giving the desired lost motion for the purpose described above.

40 In order to hold the slide E in the closed position, I provide a hooked extension e^2 which engages the bolt g of the lock G carried by a door D' hung at one end of the receptacle D. The lock G on the door retains the slide in its closed position, preventing it from being withdrawn until the bolt g is retracted, then as the bolt g is retracted it is withdrawn from the hooked member e^2 45 and a spring e^3 returns the slide E to its normal position, re-setting it with the slot d' open so that when the door in the end of the drawer is closed the drawer can be pushed into the box and locked and the slide 50 will be in position so as to allow the fare to pass from the chute into the receptacle. The spring e^3 is mounted on a rod d^2 , in the present instance carried by a bracket d^3 secured to the underside of the top plate d of the receptacle, this rod passes freely through a projection g^3 on the slide E.

55 In order to prevent the releasing of the slide E by jarring the receptacle, I notch the bolt g of the lock G at g' and make a slight rib on the end of the hook member e^2 ; the

retracting of the bolt will force the rib of the hooked member out of the notch g' but it cannot be jarred loose.

Many different arrangements may be designed for accomplishing the closure of the receptacle on the operation of the lock which fastens the receptacle to the box. For instance, there may be a lever and slide connection, as shown in Fig. 15, instead of the rack and segment, and the mechanism may be placed at one side of the receptacle so as to allow for the insertion of a separate cash box and this cash box may be made either singly or in any number of compartments, as desired, and as fully described in the application for patent filed April 28, 1908 under Serial Number 429,698.

The bolt on either lock may be of the spring latch type illustrated in the drawings, or may be a bolt of the type which must be actuated when the receptacle is placed in position in the box or when the door is closed.

It will be noticed that I have shown a spring keeper α^2 attached to the front edge of the box directly above the lock of the receptacle and I have beveled the bolt of this lock so that when the lock is forced into position the bolt of the lock will not yield but the spring keeper will yield and will spring in front of the bolt as soon as the receptacle is in position.

I claim:

1. The combination in a fare box, of a receptacle for the fares, said receptacle having a fare receiving opening, a lock for securing the receptacle in position in the box, and means for closing the opening actuated by the lock that secures the receptacle to the box.

2. The combination in a fare box, of a receptacle mounted in the box and having a fare receiving opening, means for closing said opening, a lock for securing the receptacle to the box, and mechanism actuated by the lock to close the opening before the locking bolt is retracted.

3. The combination in a fare box, of a removable receptacle mounted in the box having an opening for the passage of fares into the box, a lock for securing the receptacle to the box, means for closing the opening in the receptacle, and mechanism connecting the lock mechanism with the closing mechanism in such a way that the closing mechanism will be actuated so as to close first the opening and then retract the bolt of the lock to release the box.

4. The combination in a fare box, of a receptacle for the fares, having an opening for the passage of the fares into the box, a lock for securing the receptacle in position in the box, a door for the receptacle so that access may be had to the interior of the receptacle, a lock for the door, means for closing the opening, and mechanism connecting said

means with the lock that secures the receptacle to the box so that the receptacle will be closed before it is withdrawn from the box, with means connecting the said closing device with the door lock so that it will be released when the door is opened.

5. The combination of a fare box, a receptacle mounted therein, and having an opening communicating with the fare receiving opening of the box, a lock for securing the receptacle to the box, a slide for closing the opening in the receptacle, means connecting the spindle of the lock to said slide, the parts being so arranged that a given 10 amount of lost motion will be provided so that on turning the spindle of the lock the slide will close the opening prior to the withdrawal of the bolt to release the receptacle from the box.

15 6. The combination in a fare box, of a receptacle for receiving fares, said receptacle having a slot in its upper surface, a lock for securing the receptacle to the box, a slide for closing the slot, a shaft connected to the 20 spindle of said lock, a toothed segment mounted on the shaft, said segment having a slotted hub, a pin projecting from the shaft adapted to the slot in the hub, a rack secured to the slide, and a spring tending to 25 keep the slide clear of the opening, the parts being so arranged that on the first movement of the lock the slide will close the opening in the box and then the bolt will be retracted so as to allow the receptacle to be removed 30 from the box.

35 7. The combination in a fare box, of a receptacle for fares having an opening, a slide for closing the said opening, a lock for securing the receptacle to the box, said lock 40 being connected to the slide, said slide having a hooked extension, a door in the end of the box, a lock for securing the door, the bolt of the lock being recessed to receive the hook of the extension of the slide so that when the 45 slide is moved so as to close the opening in the box the hooked extension will engage the bolt of the door lock and will be held closed until the door lock is operated, causing the bolt to be retracted and freeing the hooked extension, and a spring for returning the slide to its normal position.

50 8. The combination in a fare box, of a receptacle mounted therein having an opening for the passage of fares, a lock for securing the receptacle to the box, means for closing the opening connected with the said lock, and a door having a lock, on the opening of which access may be had to the box.

55 9. The combination in a fare box, of a receptacle mounted therein and having an opening for the passage of the fares, a slide adapted to close the opening, a spring tending to hold the slide in its normal position so as to allow for the passage of fares into

the box, means for locking the slide in its 65 closed position, a door by which access may be had to the interior of the box, and a lock for said door, the parts being so arranged that on the opening of the door the slide will be released.

70 10. The combination in a fare box, of a receptacle for the fares, having an opening for the passage of the fares, means for closing the said opening, a lock for securing the receptacle to the box, said lock having a bolt 75 and spindle, a handle on the spindle, means connecting the spindle with the means for closing the opening in the box, and means for locking the spindle.

11. The combination in a fare box, of a 80 fare receptacle mounted therein and having an opening for the passage of the fares, a slide for closing the said opening, a lock for securing the receptacle to the box, said lock having a bolt and spindle, a shaft connected 85 to the spindle, and means for connecting the shaft with the slide, the lock having a key operated means for locking the spindle, and a handle connected to the spindle for turning the spindle and the shaft.

90 12. The combination in a fare box, of a receptacle having an opening for the passage of fares, a lock for securing the receptacle to the box, said lock having a spindle and locking means, said locking means being actuated 95 by a key, and a handle for turning the spindle independently of the key, the spindle being connected to the slide for closing the opening in the receptacle, a door in the receptacle, a lock for the door, said lock also retaining 100 the slide in a closed position when the first mentioned lock is operated to allow for the withdrawal of the receptacle from the box.

13. The combination in a fare box, of a receptacle having an opening for the passage 105 of fares, a slide closing said opening, a spring for returning the slide to its normal position, a rack on the slide, an operating shaft, and a segment on the shaft meshing with the rack.

110 14. The combination in a fare box, of a receptacle for the fares having an opening therein for the passage of fares into the box, a slide, a rack on the slide, a spring for returning the slide to its normal position, an 115 operating shaft, a segment loosely mounted on the shaft and meshing with the rack on the slide, a slot in the hub of the said segment, and a pin projecting from the shaft into the slot so that there will be a certain 120 amount of lost motion between the shaft and segment.

15. The combination in a fare box, of a receptacle, said receptacle having an opening for the passage of fares into the box, a lock 125 for securing the receptacle to the box, a shaft actuated by the lock, a segment loosely mounted on the shaft, means for connecting

the segment with the shaft, a slide for closing the opening in the receptacle, and means connecting the segment with the slide.

16. The combination in a fare box, of a receptacle mounted therein having an opening for the passage of fares, a slide closing said opening, means for actuating the slide, a hooked extension on the slide, a door hinged to the box and having a lock, the bolt of the lock being recessed for the reception of the hooked extension of the slide when the slide is moved to the position to close the opening in the box.

17. The combination in a fare box, of a receptacle mounted in the fare box and hav-

ing an opening for the passage of fares into the box and having a door, said receptacle having a door provided with a lock on the opening of which the fares can be removed from the box, and an independent lock on the receptacle for locking the receptacle to the fare box. 20

In testimony whereof, I have signed my name to this specification, in the presence of two subscribing witnesses.
